11 Claims. (Cl. 19—106)

ABSTRACT OF THE DISCLOSURE

The upper roller of the pair of nip forming rollers is grooved in a manner to provide sharp edges with the peripheral surface of the roller which are pointed in the direction of rotation of the roller. The sharp edges serve to seize and pull fleece from the intermediate filleted roller adjacent the doffer.

This is a continuation of application Ser. No. 319,441, filed Oct. 28, 1963, now abandoned.

The invention relates to an apparatus for removing and taking over the card-web or fleece from the doffer of a carder.

It has been proposed to remove the fleece from the doffer of a carding machine by an air current continuously flowing from the inside of the doffer to the outside. This necessitates the provision of a complicated, perforated and expensive doffer cylinder as well as a special fillet for the doffer, permitting exit of air between the fillet wires. A delicate, adjustable air distributing system must be provided inside the doffer cylinder which assures equal speed along the axis of the doffer cylinder of the air streams leaving the doffer. Considerable amounts of compressed air must be made available which increases first cost and the expenses connected with the operation of the aforescribed conventional system. The fleece separated from the doffer cylinder is taken over by a pair of rollers, one of which is perforated for affording discharge of the air leaving the doffer. Accumulation of fly in the perforated roller is unavoidable and makes removal of the fleece unreliable. It has been proposed to replace the aforementioned pair of rollers by a device whereby the fleece is taken over from the doffer by an intermediate roller having rigid filleting and fed therefrom into the nip of a pair of rollers having plain surfaces whereupon the fleece is fed to a pair of calender rollers. This arrangement has the disadvantage that the fleece is not automatically drawn into the nip formed by the pair of rollers, when the apparatus is started and that it is therefore necessary to wet the upper roller of the pair of rollers to assure adhesion of the fleece.

An apparatus is known for taking over the card-web or fleece from the doffer or a carder, wherein a small roller fitted with a flexible fillet and a still smaller roller having a rigid fillet are provided for gripping the bottom side of the fleece and feeding it into a pair of press rollers followed by the conventional calender rollers. In order to obtain operating reliability a draft of about 10 to 15% between the roller having a rigid fillet and the press rollers is effected so that the entire draft between the doffer and the calender rollers amounts to 30 to 35%, which is extremely high. Aside from the disadvantage that the fleece does not automatically move to the press rollers, when starting the apparatus, there is a possibility that the fleece which adheres only to the bottom side of the rollers drops down during operation of the apparatus and may rupture. In order to effect temporary adhesion of the fleece to one of the press rollers, the roller must

2

be wetted by the operator to assure drawing of the fleece into the nip formed by the press rollers. This wetting operation is very impracticable. Because of the required very great draft, the fleece delivered by the doffer must be heavy and it has been found that this impairs the carding operation when the fleece passes from the main carding cylinder to the doffer. It has been tried to effect direct taking over of the fleece from the doffer by a pair of rollers having smooth surfaces. This is not possible when operating at high speed and particularly when processing short staple. The reason is that a doffer effecting good carding has hooks or edges at the points of the filleting which retain short staple.

Purely mechanical fleece doffing devices are known whereby the fleece is taken over from the doffer by a pair of rollers provided with crossing spiral grooves and guided therefrom to the calender rollers. Each grooved roller is provided with a scraper. A satisfactorily working fillet of a doffer must be sharp and rough so that the fibres are properly seized between the main carding cylinder and the doffer, and the main carding cylinder is not overloaded and dropping of the fleece to the floor between the main carding cylinder and the doffer is avoided. If these requirements are met, a pair of grooved rollers cannot pull the fleece from the doffer. The scrapers cannot prevent pulling of the fleece by the spiral grooves and through the latter beneath the scrapers.

It is an object of the invention to provide a system for taking over the card-web or fleece from the doffer of a carder which system avoids the disadvantages of conventional arrangements and which assures automatic doffing and delivery of the fleece under all possible operating conditions and also when operating at high speeds and processing very short staple material. With the system according to the invention the carding effect of the doffer is not impaired and the only manual operation required is the feeding of the fleece to the calender rollers when starting the apparatus.

With the system according to the invention the fleece is automatically moved close to the calender rollers, also at difficult situations, for example when the fleece is very thin or ruptured and the rollers of the take-over apparatus rotate slowly.

In the following, critical situations are listed which situations are successfully coped with by the system according to the invention.

(A) The main carding cylinder and the flats do not contain any fibres, i.e., are empty, and

(A1) The feeding mechanism and the doffer of the carder are started and the main carding cylinder, the take-in, and the apparatus for taking over the fleece from the doffer operate at very slow speed. In this case initially a very thin fleece is produced which is difficult to remove from the doffer.

(A2) The feeding mechanism and the doffer are started and the main carding cylinder, the take-in and the apparatus for taking over the fleece from the doffer operate at normal operating speed. In this case too, the initially produced fleece is thin.

(B) The main carding cylinder and the flats are filled with fibres as required for normal operation, and

(B1) The feeding mechanism and the doffer are started and the main carding cylinder, the take-in and the apparatus for taking over the fleece from the doffer operate at very slow speed. In this case a fleece of normal operating thickness is produced but delivered very slowly.

(C) The carder is operated at normal speed and the doffer and the feeding mechanism are stopped during a considerable period of time. In this case rupture of the fleece occurs between the main carding cylinder and the doffer which is noticeable a short time after the doffer is restarted and which is followed by a continuous fleece.

(D) The fleece on the doffer is interrupted fully or partly for some time. This can be the case if the sliver which is fed to the carder is ruptured or if there is no good connection between the running-off end of an exhausted lap and the running-on end of a new lap.

The apparatus for taking over the fleece from the doffer of a carder must accurately and reliably operate in all above listed situations so that the fleece is immediately and completely removed from the doffer and presented to the calender rollers. The conventional mechanisms, though satisfactorily coping with some of the listed situations, are not satisfactory in all these situations.

The mechanism according to the invention is satisfactory in all above listed situations. This is due to the arrangement of a filleted intermediate roller adjacent to the doffer, a pair of rollers comprising an upper roller and a lower roller cooperating with the intermediate roller for pulling the fleece therefrom, and a guide roller forming a nip with said lower roller.

The upper roller of the aforementioned pair of rollers is provided with helical grooves forming sharp edges at the periphery of the roller pointing in a direction substantially coincident to the direction of the circumferential movement of the roller for seizing and pulling the fleece from the intermediate roller. In order to reliably move the ends of the fleece through the apparatus a nozzle is placed above the grooved roller and the guide roller and in the proximity of the ends of these rollers for discharging an air stream adjacent to and in a direction parallel to the axes of these rollers. The air adjacent to the grooved roller is diverted by said helical grooves to flow in a direction opposite to the direction of rotation of the grooved roller. The guide roller may be mounted to act as a press roller and may be placed parallel with or at an angle with the lower roller. In the latter case the aforementioned air currents must flow in the direction of the increasing distance of the guide roller from the lower roller.

The novel features which are considered characteristic of the invention are set forth with particularity in the appended claims. The invention itself, however, and additional objects and advantages thereof will best be understood from the following description of embodiments thereof when read in connection with the accompanying drawing, wherein:

FIGURE 1 is a diagrammatic sectional view of a portion of a carder.

FIGURE 2 is a sectional view of a portion of the carder shown in FIGURE 1, the section being made along line II—II of FIGURE 1.

FIGURE 3 is a sectional view of a portion of the modified carder shown in FIGURE 7, the section being made along line III—III of FIGURE 7.

FIGURES 4 and 5 are diagrammatic cross sectional views of portions of two modifications of an intermediate roller.

FIGURE 6 is a cross sectional view of a grooved roller forming part of the carders shown in FIGURES 1 and 7.

FIGURE 7 is a diagrammatic sectional view of a modified carder.

FIGURE 8 is a schematic part sectional view of a detail of the carder shown in FIGURE 7.

FIGURES 9 and 10 are diagrammatic top views of roller groups with the cover removed.

Referring more particularly to FIGURE 1 of the drawing, numeral 1 designates a carder frame having a cover 2 and including supports 3 at either side for a filleted roller 4 whose diameter is about 120 mm. and which is so close to the points 5 of the clothing or fillet of a doffer 6 as to be operatively associated therewith so that taking over of the card-web is assured, the distance between the points 5 and the points of the clothing or fillet of the roller 4 being 0.2 to 0.3 mm. The garniture or fillet of the intermediate roller 4 may consist of low saw teeth 7 whose height h (FIG. 4) is about 2 to 3 mm.

The angle α formed by the active flank of a tooth with a straight line connecting the point of the tooth and the center Z of the roller 4 is about 15° to 25°. This small angle α and the low height h facilitate removal of the web from the roller 4 by the subsequent rollers 8 and 9.

FIGURE 5 shows a modification of the garniture or fillet of the roller 4. The teeth 7 shown in FIGURES 1 and 4 are replaced by flexible wires 11 whose free length h' is 2 to 3 mm. Each wire forms with a straight line connecting the free end of the wire and the axis of the roller 4 an angle β of about 15° to 25°. A paddle roller 12 is placed opposite the nip formed by the rollers 6 and 4 and is rotated at about 1500 r.p.m. for producing an axial air whirl in the space between the cover 2 and a cover 13 covering the doffer roller 6 and extending to said nip. By providing a cover 13 as shown formation of web or sliver rolls, which can be removed by hand only, is avoided.

In the modification shown in FIGURE 7 a counter-clockwisely rotating roller brush 12' is provided which has an effect similar to that of the paddle roller 12 in FIGURE 1. The high speed of rotation of the elements 12 or 12' produces centrifugal forces which throw off the fibrous material and have a self-cleaning effect.

The periphery of an upper longitudinally grooved roller 8 is near the points of the filleting of the intermediate roller 4 and forms a nip with a plain lower roller 9. The distance between the periphery of the roller 8 and the points of the filleting 7 (FIG. 4) or 11 (FIG. 5) is about 0.2 to 0.3 mm. The periphery of the roller 9 is also spaced from the points of the filleting of the roller 4 by a small distance, i.e., 2 to 3 mm. The roller 8 is provided with four or more grooves 14 whose depth is about 6 mm. and whose width is about 10 mm. The grooves 14 extend helically around the roller 8, the pitch being about 400 mm., at a roller diameter of about 70 mm. The helices along which the grooves are placed need not have a constant pitch. The number of the grooves depends on the diameter of the roller 8. The leading faces 15 of the teeth defined between the grooves 14 of the roller 8 form with the tangent t on the cylindrical surface of the rollers an angle δ of about 45° (FIG. 6). In this way sharp edges are formed at the periphery of the upper roller 8, the edges pointing in a direction substantially coincident to the direction of the circumferential movement of the roller 8.

A guide roller 16 having a plain cylindrical surface and a diameter equal to that of the roller 9 is arranged in close proximity of the rollers 8 and 9 and spaced 0.2 to 0.3 mm. therefrom. The roller 16 does not form a clamping nip with the rollers 8 and 9.

The relation of the rotational speeds of the afore-described rollers are preferably as stated in the following table wherein V_a is the circumferential speed of the doffer 6:

Circumferential speed V_4 of roller 4 = 1.02 to $1.04 \times V_a$
 Circumferential speed V_8 of roller 8 = $0.95 \times V_a$
 Circumferential speed V_9 of roller 9 = $1.06 \times V_a$
 Circumferential speed V_{16} of roller 16 = $1.06 \times V_a$

Deviations of 1 to 2% from the above values are unimportant.

Scrapers 17 and 18 are provided on the rollers 16 and 9, respectively, and point opposite to the direction of the peripheral movement of the rollers.

In lieu of the guide roller 16 a press roller 19 as shown in FIGURE 8 may be provided. The roller 19 has trunnions extending into slides 21 slidably in slots 20 in the supports 3, the slots extending toward the rotation axis 70 of the roller 9. Springs 22 press the slides toward the roller 9 and effect the desired compression of the fleece or fibrous web passing through the nip formed by the rollers 9 and 19. In order to counteract bending, the press roller 19 is slightly barrel-shaped. If this is not desired the press roller may be placed at a slant with respect to the

roller 9 by laterally displacing the guides for the slides 21 as shown in FIGURE 10. In this case the end of the roller 19 which is closest to the grooved roller 8 is spaced about 1 to 2 mm. (a) from the grooved roller and the second end of the roller is spaced about 20 mm. (a') from the grooved roller 8, if the width of the carder is 400 mm.

As seen in FIGURES 1 and 2 air is blown through a nozzle 23 at a hydrostatic head of about 20 to 50 mm. in a direction substantially parallel with the rotation axes of the rollers into the space between the grooved roller 8 and the guide roller 16 or the press roller 19 in FIGURE 7. The air current must be so introduced that the air which is adjacent to the grooved roller 8 is diverted in a downward direction by the grooves 14. This causes a velocity component V_u in a direction opposite to the movement of the grooved roller (FIG. 2). In the illustrated example, the air flows at diminishing speed from right to left as shown by arrows and moves above the grooved roller 8 and the paddle roller 12 to an outlet 24.

In the modification shown in FIGURES 3 and 7 a channel 25 extends in the cover 2 over the entire width of the carder and conducts air at a superatmospheric pressure of about 20 to 50 mm. hydraulic head. The air is blown between the rollers 8 and 19 in a direction substantially parallel with the rollers by means of a plurality of suitably shaped nozzles 26 connected to the channel 25. If the roller 19 is placed at a slant with respect to the roller 8, the nozzles are so placed as to discharge air from the channel 25 in the direction of the increasing distance between the rollers 19 and 8. The modification shown in FIGURE 3 is not limited to the application to an apparatus shown in FIGURE 7 but may be used in combination with the apparatus shown in FIGURE 1.

When starting the carder, the apparatus according to the invention operates as follows:

The end of the fleece or fibrous web adhering to the lower side of the doffer is seized by the fillet of the roller 4 and is wiped therefrom by the sharp edges of the grooved roller 8 and pushed toward the nip formed by the rollers 8 and 9. It is possible that, initially, the end of the fleece is not entirely seized by the roller 8 and parts of the fleece remain on the intermediate roller 4. These parts of the fleece are wiped from the roller 4 by the air whirl produced by the roller 12 or by the brush roller 12' before they reach the doffer 6 and are sucked through the outlet 24. The fleece 27 taken from the doffer 6 moves from the nip formed by the rollers 8 and 9 over the roller 9 and between the rollers 9 and 16 or 19 toward the calender rollers 28. If the fleece is retained on the roller 8 for some reason and moves upwards between the roller 8 and the roller 16 or 19, the air current directed downwards by the grooves 14 loosens the fleece and blows it unto the roller 16 or 19 which guides the fleece to move downward into the space opposite the calender rollers 28. The air current which is diverted by the grooves 14 serves as a precaution assuring correct operation of the apparatus under all adverse conditions which may occur when starting the carder. The air current supplied through the nozzle 23 or the conduit 25 may be stopped when the fleece arrives correctly in the space containing the calender rollers.

We claim:

1. In an apparatus for taking up a fleece, a filleted roller for conveying the fleece, a pair of rollers spaced from said filleted roller for pulling the fleece therebetween from said filleted roller, said pair of rollers comprising a substantially smooth surfaced lower roller and an upper roller spaced from said lower roller, said upper roller having a plurality of grooves therein, each pair of adjacent grooves defining a tooth therebetween, each said tooth having a leading face forming a sharp edge with the peripheral sur-

face of said upper roller for seizing and pulling the fleece on said intermediate roller.

2. An apparatus as set forth in claim 1 wherein each said sharp edge is pointed in a direction substantially coincident to the direction of rotation of said upper roller.

3. In an apparatus as set forth in claim 1 wherein said grooves are helically directed with respect to the axis of said upper roller.

4. In an apparatus as set forth in claim 1, a guide roller positioned adjacent said pair of rollers opposite said filleted roller for guiding the fleece from between said pair of rollers.

5. In an apparatus as set forth in claim 4, means positioned above and between said upper and said guide rollers for blowing an air stream adjacent to and parallel with said upper roller.

6. An apparatus as defined in claim 4 including means associated with said guide roller for pressing said guide roller against said lower roller.

7. An apparatus as defined in claim 1, wherein said upper roller is placed closer to said filleted roller than said lower roller.

8. An apparatus as defined in claim 1, wherein the rollers of said pair of rollers are in close proximity.

9. An apparatus as defined in claim 1, wherein said guide roller is in close proximity of the rollers of said pair of rollers without forming a clamping nip therewith.

10. An apparatus for taking over the fleece from the doffer of a carding machine, comprising, in combination, a filleted intermediate roller placed adjacent to the doffer to remove a fleece therefrom,

a pair of rollers comprising a lower and an upper roller adjacent to said intermediate roller for pulling the fleece therefrom, said upper roller including helical grooves therein,

a guide roller placed adjacent to said pair of rollers opposite said intermediate roller, and means placed above and between said upper roller and said guide roller for blowing an air stream adjacent to and parallel with the axial direction of said upper roller and said guide roller, said helical grooves being so arranged as to cause a diversion of the air adjacent to said upper roller in a direction opposite to the circumferential movement of said upper roller.

11. An apparatus for taking over the fleece from the doffer of a carding machine, comprising, in combination, a filleted intermediate roller placed adjacent to the doffer to remove a fleece therefrom,

a pair of rollers comprising a lower and an upper roller adjacent to said intermediate roller for pulling the fleece therefrom,

a guide roller placed adjacent to said pair of rollers opposite said intermediate roller, and

means placed between the doffer and said intermediate roller for producing an air whirl along the doffer and said intermediate roller to wipe any remaining fleece on said intermediate roller therefrom.
